UNITED STATES PATENT OFFICE.

FRANCIS W. BRADY, OF ENGLEWOOD, NEW JERSEY.

LUBRICATING-OIL FEED FOR RECIPROCATING ENGINES.

No. 849,325.

Specification of Letters Patent:

Patented April 2, 1907.

Application filed April 14, 1906. Serial No. 311,767.

To all whom it may concern:

Be it known that I, FRANCIS W. BRADY, a citizen of the United States, residing at Englewood, county of Bergen, State of New Jersey, have invented certain new and useful Improvements in a Lubricating-Oil Feed for Reciprocating Engines; and I do hereby declare the following to be a full, clear, and exact description of the invention, such as will enable others skilled in the art to which it appertains to make and use the same.

The object of the invention is to provide efficient mechanism for the positive and regular feed of oil to the bearings of reciprocating engines.

The invention will be understood from a reference to the drawings and a reading of the following description of the form in which I prefer to embody it.

Referring to the drawings, Figure 1 is an elevation, partly in section, of parts of a reciprocating engine provided with lubricating mechanism made in accordance with my invention. Fig. 2 is a side elevation of the same parts, also partly in section. Fig. 1 is a view of Fig. 2 from the left. Fig. 3 is an elevation of the casing of my improved oil-pump, showing the means for attaching it to its support. Fig. 4 is a side elevation of the pump assembled, and Fig. 5 is a sectional view of the pump. Fig. 6 is an elevation, partly in section, of the oil-cup mounted on the collar surrounding the wrist-pin of the piston; and Fig. 7 is an elevation of the oil-cup looking at the right of Fig. 6 with parts broken away.

Referring to Figs. 1 and 2, *a* is an outline of the engine-cylinder, *b* is the piston, and *c* is the piston-rod or pitman, having a collar *d* at its lower end; which surrounds the crank-pin of the engine, (not shown,) and a collar *e*, which surrounds the wrist-pin in the piston-head. The parts above mentioned may be of any ordinary construction and form no part of my invention.

On the pitman *c* is a clamping-ring *f*, which carries the oil-pump *g*. The exit-passage of the oil-pump is connected by a pipe *h* with the lower end of the oil-cup *i*, mounted on the collar *e* and provided at its upper end with an overflow-passage *j*, which is connected with the pipe *k*, by which the overflow from the oil-cup is carried down the length of the pitman to the crank-pin.

Rigidly secured to the lower end of the cylinder *a* is a bracket *l*, carrying an oil-reser-

voir *m*, provided with an inlet-pipe *n*, supplying oil from a reservoir, (not shown,) and an overflow-pipe *o*, whereby the oil in the reservoir *m* is maintained at a constant level. 60 The reservoir *m* is also provided with drip-plates *p* for catching the oil dripped and splashed by the pump. The bracket *l*, carrying the reservoir *m*, projects inwardly, so that the oil-reservoir is supported directly beneath the pump *g*. Rigidly secured to the inside of the piston is a pin *q*, which extends into engagement with a lever-arm on the pump *g* and is held in fixed relation thereto throughout the stroke of the piston. 70

Referring to Figs. 3, 4, and 5, it will be seen that the casing of the pump *g* has cast on it a bracket *r*, provided with holes for the screws *s*, by which it is rigidly secured to the clamping-ring *f*, and thereby to the pitman *c*. At right angles to the bracket *r* is a bracket *t*, forked at its upper end and between the arms of which the three-armed lever *u* is pivoted. One arm of the lever *u* extends into a bearing in the upper end of the 80 pump-plunger *v*, and the other two arms of the lever are in a position to be engaged by the pin *q* on the engine-piston. (See Figs. 1 and 2.) The pump is provided at its lower end with an inlet-passage in which there is a 85 suction-valve *w*, cone-shaped at its lower end and provided with appropriate oil-pas- sages. This suction-valve *w* is pressed into engagement with a beveled seat at the lower end of the inlet-passage by means of a com- pression-spring *x*. Immediately above the inlet-passage and at the side of the piston- chamber is an outlet-passage, which is pro- 90 vided with a pressure-valve *y*, which is pressed into engagement with its seat by compression-spring *z*. This exit-passage communicates with the pipe *h*. A short dis- tance above the outlet-passage and on the opposite side of the piston-chamber is an in- 95 let-port which communicates with the cham- ber *a'*, having a restricted opening *b'* at its upper end. By this construction when the plunger of the pump is withdrawn the oil is sucked up into the pump-chamber during the first part of the stroke and while the port 100 from the chamber *a'* is covered. As soon as this port is uncovered and during the remain- der of the outstroke the contents of the cham- ber *a'* are sucked into the pump, and the suc- 105 tion through the oil-inlet port is relieved. 110 Upon the instroke of the plunger the con- tents of the pump-chamber are forced back

into the chamber a' , and as soon as the port to that chamber is closed by the downward movement of the plunger the oil in the lower part of the chamber is forced through the outlet-passage into the feed-pipe h . I am thus enabled to use an oil-pump which has a greater length of stroke and a greater diameter of plunger without increasing the amount of oil fed, and thus avoid the necessity which would otherwise exist of using a pump of an extremely small stroke and diameter of plunger. I prefer so to shape the lever u that the suction-stroke of the pump is completed before the end of the pump emerges from the reservoir m ; but if for any reason it is inadvisable or impracticable to do this my improved construction of pump will have a further peculiar advantage in the relations in which I have described it, because the position of the inlet-port from the chamber a' may be made such that the oil is drawn through the oil-inlet port of the pump only during that portion of the stroke in which the tip of the oil-pump is submerged in the reservoir m , and after the tip of the pump has emerged from the reservoir and during the remainder of the stroke the pump sucks in the contents of the chamber a' .

In Figs. 6 and 7 I have shown the oil-cup, which is rigidly secured to the collar of the wrist-pin by means of a bolt passing through the lug c' on the oil-cup and into a corresponding lug on the collar e . This oil-cup is provided with a vertical chamber d' , the lower end of which communicates with the oil-supply pipe h and the upper end of which is closed by a screw-cap e' . A port f' , opening into the side of this chamber, communicates through the oil-duct g' (see Figs. 1 and 2) with the wrist-pin. This duct is preferably filled with a wick, by means of which the oil is evenly fed from the chamber d' to the wrist-pin. Above the port f' is the overflow-passage j , into which the elbow-pipe h' is fitted. The pipe h' is coupled in any suitable manner with the overflow-pipe k , by which oil is led down the length of the pitman c to the crank-pin of the engine. The pipes h and k are securely fastened in position on the pitman c by means of suitable collars j' .

The operation of the oil-feed is as follows: When the piston b is at the end of its instroke, the pump g is in the position shown in full lines in Figs. 1 and 2, and the position of the pin q with respect to the arm of the lever u is as shown in full lines in those figures. Supposing that the crank of the engine is rotating in a counter-clockwise direction, as the pitman c starts its outward movement it is inclined toward the left, carrying with it the pump g and the lever u . The pin q , which is secured to the interior of the piston-head, does not, however, partake of this sidewise movement, and the consequent relative

movement of the pin q and the lever u causes the pin q to engage with the right-hand arm of said lever and to rotate it on its pivot to press down the plunger of the oil-pump, thereby forcing the oil in the pump upward through the pipe h into the oil-cup i . This position of the pump is shown in dotted lines at A in Fig. 1. As the pitman c continues its outward movement it again approaches the vertical line, causing the pin q and the lever u to assume the relative positions shown in dotted lines at B in Fig. 1. During this time the pin has merely ridden along the surface of the lever u and has not moved the piston of the pump.

The elliptical path of the lower end of the pump is shown in dotted lines in Fig. 1, and it will be seen that at position B the lower end of the pump is submerged in the oil in the reservoir m . As the pitman c passes beyond the center and becomes inclined toward the right in Fig. 1 the pin q engages with the left-hand arm of the lever u and rotates it on its pivot and draws out the plunger, thus drawing up oil from the reservoir m into the pump. As the pitman moves inward again the pump assumes a position shown in dotted lines at C in Fig. 1, in which position the plunger of the pump is drawn out and the oil is held in the pump. As the pitman reaches the end of its instroke the pump again assumes the position shown in full lines in Figs. 1 and 2, and on the next outward movement of the pitman the oil is expelled into the pipe h , as already described. The oil is thus fed drop by drop up the pipe h and into the oil-cup i , from which it is fed by the duct g' to the wrist-pin and by the overflow-pipe k to the crank-pin. Instead of having the pump mounted on the pitman and the actuating-pin q secured to the piston-head it would of course be possible to reverse the parts and have the pump mounted on the piston-head and the actuating-pin mounted on the piston.

I prefer to fill the chamber a' full or partially full of oil, so that when the port between this chamber and the pump-chamber is opened oil will be sucked from the chamber a' of the pump-chamber; but it is obvious that I may fill the chamber with other suitable fluid or leave it empty, allowing the pump to suck air through the chamber a' into the pump-chamber while the port between these chambers is open.

I believe that the nature and advantages of my improvements will be clearly understood from the above description of the form in which I prefer to embody them, though it will be understood that my improvements may be embodied in other forms without departing from the spirit of my invention.

What I claim is—

1. In a lubricating-oil feed for reciprocating engines, an oil-pump secured to the en-

gine-pitman, and partaking of the sidewise movement thereof and a projection in the path of the movement of the pump and engaging therewith to actuate it during its sidewise movement.

5. 2. In a lubricating-oil feed for reciprocating engines, an oil-pump rigidly secured to the engine-pitman in such manner as to partake of the sidewise movement thereof, and means whereby the pitman in its sidewise movement will operate the pump to feed oil to the engine-bearings.

15. 3. In a lubricating-oil feed for reciprocating engines, an oil-pump carried by the engine-pitman, an actuating-lever for said pump, and a projection on the engine-piston engaging said lever, whereby the sidewise movement of the pitman actuates the oil-pump.

20. 4. In a reciprocating engine, a piston having a wrist-pin, a pitman provided with bearings for the said wrist-pin and for a crank-pin, an oil-cup communicating with the wrist-pin bearings and provided with an 25 overflow-passage, an oil-pump mounted on the pitman and actuated by the sidewise movement thereof to feed oil to the cup, and an oil-pipe leading from the overflow-passage in the oil-cup to the bearings for the 30 crank-pin, substantially as described.

35. 5. In a reciprocating engine, a piston having a wrist-pin, a pitman provided with bearings for the said wrist-pin and for a crank-pin, an oil-cup plunger actuated by the sidewise movement of the pitman, a chamber for said plunger having an oil-inlet and a second inlet so constructed and arranged as to be opened after the suction-stroke of the plunger has begun, the said chamber also having 40 a discharge-port, an oil-cup communicating with the wrist-pin bearings and having an overflow-port, a pipe connecting the discharge-port of the pump with the oil-cup, and a second pipe leading from the overflow- 45 passage in said cup to the bearings for the crank-pin, substantially as described.

50. 6. In a lubricating-oil feed for reciprocating engines, an oil-pump actuated by the movement of the engine-piston, and having an oil-inlet to the pump-chamber, and a second inlet to said chamber so constructed and arranged as to be opened after the suction period of the pump has begun.

55. 7. In a lubricating-oil feed for reciprocating engines, an oil-pump plunger actuated by the movement of the engine-piston, a chamber for the plunger having an oil-inlet at its bottom, a second inlet above the oil-inlet, and a discharge-port, and an oil-pipe leading 60 from the discharge-port to bearings on the engine.

65. 8. In a lubricating-oil feed for reciprocating engines, an oil-pump mounted thereon, an oil-reservoir also mounted on said engine, means for causing the pump to dip into the

reservoir at intervals and means for creating the suction period of the pump while it is dipping into the reservoir.

9. In a lubricating-oil feed for reciprocating engines, an oil-pump mounted thereon, 70 an oil-reservoir also mounted on said engine, means for causing the pump to dip into the reservoir at intervals, means for creating the suction period of the pump while it is dipping into the reservoir, and means for maintaining constant the oil-level in the reservoir. 75

10. In an oil-feed for reciprocating engines, an oil-pump rigidly secured to the engine-pitman and partaking of the sidewise movement thereof, an oil-reservoir so mounted 80 in the path of the movement of the pump that the pump dips into it at the end of the outward stroke of the pitman, and means actuated by the sidewise movement of the pump to create its suction period while it is 85 dipping into the reservoir.

11. In a lubricating-oil feed for reciprocating engines, an oil-pump mounted thereon, an oil-reservoir also mounted on said engine, means for causing the pump to dip into the 90 reservoir at intervals, an oil-inlet to the pump-chamber, a second inlet to the said chamber, and means for withdrawing the pump-plunger while the pump is dipping into the reservoir, the second inlet being so 95 constructed and arranged as to be opened after the pump-plunger is partially withdrawn.

12. In a reciprocating engine, a piston having a wrist-pin a pitman provided with 100 bearings for the said wrist-pin and for a crank-pin, an oil-pump mounted on the pitman, an actuating-lever for the pump, a projection on the piston engaging with the lever, an oil-reservoir mounted on the engine in the 105 path of the movement of the pump, a plunger in the pump actuated by the said lever, a chamber for the plunger, provided with an oil-inlet at its bottom, a second inlet above the oil-inlet, and a discharge-port, an oil-cup 110 communicating with the wrist-pin bearings and having an overflow-passage, a pipe connecting the discharge-port of the pump with the oil-cup, and a pipe leading from the overflow-passage in the cup to the bearings for 115 the crank-pin.

13. In a lubricating-oil feed for reciprocating engines a suction-pump provided with an induction-port communicating with an oil-supply, and an eduction-port communicating 120 with the bearing to be lubricated, and means for relieving the suction through the induction-port during the suction period of the pump.

14. In a lubricating-oil feed for reciprocating engines, a suction-pump provided with an induction-port communicating with an oil-supply, an eduction-port communicating with the bearings to be lubricated, and a second induction-port, and a chamber con- 125 130

taining oil communicating with the second induction-port the second induction-port being so constructed and arranged as to be open during a part of the suction period of the pump and a corresponding part of the expulsion period of the pump.

15. In a lubricating-oil feed for reciprocating engines, an oil-pump rigidly secured to a reciprocating part, an oil-reservoir mounted

at one extremity of the path of the movement of said pump, and drip-aprons for said reservoir, substantially as described.

In testimony whereof I affix my signature in presence of two witnesses.

FRANCIS W. BRADY.
